UNITED STATES PATENT OFFICE.

CASSIUS C. MARKLE, OF WEST NEWTON, AND ROLAND H. SMITH, OF PITTSBURG, PENNSYLVANIA.

COKE-OVEN.

SPECIFICATION forming part of Letters Patent No. 235,368, dated December 14, 1880.

Application filed March 13, 1880. (No model.)

To all whom it may concern:

Be it known that we, CASSIUS C. MARKLE, of West Newton, county of Westmoreland, State of Pennsylvania, and ROLAND H. SMITH, of Pittsburgh, county of Allegheny, State of Pennsylvania, have invented or discovered a new and useful Improvement in Coke-Ovens and in Utilizing the Product thereof; and we do hereby declare the following to be a full, clear, 10 concise, and exact description thereof, reference being had to the accompanying drawings, making a part of this specification, in which—like letters indicating like parts—

Figure 1 is a perspective view of our improved apparatus, the corner of one oven and one condenser being broken away in order to illustrate certain features of interior construction; and Fig. 2 is a perspective view, to an enlarged scale, of one of the ovens, but with 15 the oven-walls and floor shown partly in section.

Our invention relates to an improved construction of apparatus for the making of coke from soft or bituminous coals, wherein the carbonaceous gases from the ovens are carried directly to and through a series of condensers or washers, thence to a holder, and thence through pipes or passages in the inclosing walls of the oven or ovens for the reheating 25 of the same, and are finally discharged in jets into the charge inclosed in the oven, substantially as hereinafter set forth and claimed.

Our apparatus is constructed with reference, among other things, to rapidity of operation, 30 superiority of product, and the utilization of waste products.

By carrying on the process more rapidly we are enabled to secure a greater amount of product without increase of plant. By utilizing 40 waste products we lessen the expense, and by a process of treatment which drives off or consumes a minimum of carbon, and which hardens the product which results from the process, and which also eliminates objectionable impurities, we materially enhance the value 45 of the coke produced.

Our coke-oven walls A are of the usual or any suitable construction, ordinarily built up of masonry with ties or binders, and by preference so as to give a dome-shaped oven, A'.

In the fire-brick lining of this dome we build a spiral, zigzag, or other desired arrangement of pipe, a, in such manner that such pipe may be highly heated from the heat of the oven. This pipe passes down under or into the bottom of the oven, and passes around or across such oven-bottom in such manner that the contents of the pipe may be discharged therefrom through jet-holes a' at points distributed over the bottom, in any desired number, into the 55 oven proper.

The usual door for removing the charge is shown at A² and a charging-hole at A³, closed by a hinged or removable lid, as is common in such apparatus.

Ordinarily such ovens are built side by side in a row in any desired number; but for the purposes of our invention two are quite enough for illustration.

A branch pipe, D, leads from each charging-hole, which for this purpose constitutes an escape-flue to a main or trunk flue, D', and the latter discharges into a condenser, washer, or scrubber, B. The uncondensed products of combustion pass thence, by pipes D² D³, to condensers or scrubbers B' and B'', and finally the purified gas goes to a gas-holder, H, by a pipe, D⁴, where it is stored for use.

Each condenser has a pipe, b, for the introduction of condensing or washing material, a 70 trapped pipe, d, for the escape of the excess of such material, and a cock, d', for drawing off the condensation, and also a series of leaves or shelves, s, over which the condensing material flows, so as to get the largest practicable or desirable surface for condensation.

A gas-pipe, c, leads from the gas-holder to the worm-pipes a, and a branch pipe, c', leading from any suitable steam-generator, is connected with it, as shown.

A branch, e, leads to each one of a series of ejectors arranged, as at e', in the pipes D D² D³ D⁴, as a means for promoting the draft or the regular onflow of the uncondensed gas.

The proper cocks are to be added, according 95 to the requirements of the work.

By the use of such apparatus we propose to save the gas driven off in the coking operation, to utilize it in perfecting and carrying on the coking process and in improving the pro- 100

duct; also, while purifying the gas and preparing it for the uses thus designated, to save the otherwise waste elements which are condensed in the purifying operation, and by the use of steam to further purify the coke and also improve it by hardening it.

Assuming, now, that without any gas on hand the ovens are heated, charged, and ready to start, we first let on steam through the pipes 10 c' e to the ejectors e' , in order to promote the draft on the principle of the ordinary exhaust, and also to the worm-pipe a . The steam is thus superheated and discharged through the jet-holes a' into the oven. Combustion is promoted partly by the decomposition of the steam, but chiefly by the draft. The resinous and tarry ingredients are driven off with much of the other impurities, either as they exist in the coal or are produced by decomposition—15 such as sulphur and ammonia—and are carried over to the condenser B. Here they are met by a jet of water introduced by the pipe b , and the resinous and tarry ingredients are condensed and deposited in the form of what is usually known as "coal-tar." The remaining portion of the products of combustion goes then to the condenser B', where a jet or spray of weak hydrochloric acid is introduced, as before. For most purposes a solution of about one-third acid and two-thirds water will suffice for the purpose; but these proportions may be varied at pleasure.

By surface condensation, as before, the ammonia gases are here condensed into a liquid form. This, like the coal-tar previously condensed, may be drawn off and utilized in any of the ways known in the art. The remaining portion of the gas then goes to the third condenser, B², where a jet or jets of lime-water are introduced, so as by surface-condensation, as before, to condense the sulphurous gases, which deposit partly as a powder, called sometimes "powder of sulphur." This will ordinarily be held in mechanical suspension, and may be drawn off into a vat and be allowed to settle, after which it may be utilized for any desired purposes. The gas is now sufficiently purified for the uses for which we desire it, and is stored in the gas-holder II. Of course the operation thus described goes on as long as any gas is coming off from any of the ovens. Having accumulated sufficient gas for the purpose, we use it instead of the steam for promoting the coking operation, and for this purpose we introduce it into the ovens as soon as they are charged by passing it through the pipes a and jet-holes a' , as already described with reference to the steam.

An important end to be kept in view in the coking operation is the driving off of the tarry and resinous ingredients and other objectionable impurities with the least possible consumption of the carbon of the coal, since the quality of the coke is improved by the retention therein of the largest possible percentage of solid uncombined carbon. Now, by thus in-

roducing into the coke-ovens a carbureted hydrogen at a high temperature, in the manner described, we increase the draft, and also increase the temperature and carry on the coking operation from below upward instead of from above downward. We also supply to the material to be coked a considerable percentage of carbon, which unites with the impurities or undesirable ingredients of the coal and eliminates them, and thereby lessens by so much the percentage of carbon which otherwise would be taken up from the coal. Hence we drive off the impurities more rapidly and leave the coke richer in carbon, and being richer in carbon, it is so much the better as a material for the evolution of heat, and is also so much the harder, whereby it is better adapted for use in blast and smelting furnaces, cupolas, &c., where it has to sustain a heavy burden. A soft coke for such purposes is generally regarded as unfit for use. After the material in the oven has thus been brought to a state of incandescence we shut off the gas and turn on the steam. We have found that the steam at that stage of the process has a kind of washing or cleansing effect on the coke and drives or carries off still more perfectly the ammonia and sulphur, as well as other lesser impurities, if any be left; and we have also found that the steam tends to still further harden the coke with the advantage or benefit already set forth.

The principal object of carrying the gas around through the worm a is to heat it; but for this purpose we do not limit ourselves to this means, since other suitable means for doing this work may be substituted, as a stove such as is used on hot-blast pipes, or a separate fire or heating chamber, or even jets of gas escaping from or applied to the pipe in such manner that the combustion of the gas shall operate to heat the pipe; and advantageous results may be secured by using the gas in the manner described without any preliminary re-heating, or with only such reheating as the gas would get from passing through a pipe or pipes arranged in the oven-floor and discharging into the oven, as already described. For this purpose we have shown a pipe, n , branching from the pipe c , and which may lead directly or indirectly to a system of jet-holes in the oven-floor, such as are above described. In this way we adapt our improvement to coke-ovens already built, where it may be difficult or impossible to put the pipe in the lining of the dome without tearing down and rebuilding the entire oven. In the ovens as we build them the lining in which the worm a is laid is built separately, and when it burns out or when renewal or repairs are necessary it may be removed, wholly or in part, from the inside, and rebuilt or replaced in like manner; and in designating this device as a "pipe" we include therein pipes formed by perforated bricks or hollow tile placed with their openings in line, and such structure will be preferable where the

heat is so excessive as to be liable to work injury to a metallic pipe. For the floor-pipe we prefer to use a spiral, which may be made under or in the floor, either of metal or of tile; 5 but other forms may be employed—as, for example, a single pipe may run directly across the bottom, or two or more such pipes may cross each other at the center, or one or more annular pipes of metal or tile may extend 10 around or zigzag back and forth across the bottom, the jet-holes for supplying the gas or steam to the oven being distributed accordingly. Nor do we limit ourselves to a dome-shaped oven, since the same features of invention 15 may be advantageously applied to other forms of ovens, and the gas-reheating pipes may be arranged in connection with any desired part of the walls or floor which form the oven. We have found that by the means above de- 20 scribed we are enabled to carry on the coking operation so rapidly as to reduce the time necessarily occupied in the process by about one-half.

We claim herein as our invention—

25 1. In combination with a coke-oven, a system of conduit-pipes and washers or condensers for carrying off and purifying the gas produced from the oven, a gas-holder for storing the purified gas, a conduit-pipe passing from the gas- 30 holder through one or more of the inclosing-walls of the oven, for the reheating of the gas,

such pipe discharging in jets into the oven, substantially as set forth.

2. In combination with the conduit-pipes, washers or condensers, and holder, for conducting off, purifying, and storing the waste gases of a coal-coking apparatus, and a pipe leading from the holder to the oven, a series of jet-holes in the oven opening directly into the charging-space of the oven, and distributed 35 substantially as set forth, whereby the carbon necessary for driving off the impurities of the coal is furnished at various points to the charge from the purified gas so introduced, and the coke is left correspondingly rich in carbon. 40

3. In combination with a coke-oven, a conduit-pipe for carrying off the gases produced in the coking operation, a series of condensers or washers for purifying the gas, a gas-holder in which to store the purified gas, a pipe leading from such holder to and discharging in jets 45 into the oven, and means for heating such pipe at a point intermediate between the gas-holder and the oven, substantially as set forth.

In testimony whereof we have hereunto set 50 our hands.

CASSIUS C. MARKLE.
